UNITED STATES PATENT OFFICE.

HORACE EVERETT WALTER, OF RICHMOND, VIRGINIA.

HANDBAG-HANDLE.

1,374,126.

Specification of Letters Patent.

Patented Apr. 5, 1921.

Application filed October 12, 1920. Serial No. 416,373.

To all whom it may concern:

Be it known that I, HORACE E. WALTER, a citizen of the United States, and a resident of Richmond, in the county of Henrico and State of Virginia, have invented a new and Improved Handbag-Handle, of which the following is a full, clear, and exact description.

This invention relates to improvements 10 in hand bag handles and particularly to that form of handle which comprises two members and is commonly known as a split handle.

With this type of handle the two members are secured on opposite sides of the mouth of the hand bag, and when the bag is set down they tend to fall apart or away 15 from each other. It is a source of great inconvenience to travelers, especially when 20 they are carrying more than one bag, to pick up a hand bag which is equipped with the usual form of split handle.

It is an object of my invention, therefore, 25 to provide means for removably locking the two handle members of a split handle together.

A further object is to provide a locking 30 or fastening means which may be readily attached, which will be practical in use, and will not tend to increase the cost of the hand bag.

With these and other objects in view the invention consists in certain novel features of construction and combinations and arrangements of parts as will be more fully hereinafter described and pointed out in 35 the claims.

In the accompanying drawings—

Figure 1 is a perspective view of a hand 40 bag with which my improved handle is employed.

Fig. 2 is a top plan view of the hand bag, and illustrates diagrammatically the method 45 of separating the handle members when they are in locked position.

Referring in detail to the drawings, 1 represents a conventional type of hand bag wherein a pair of substantially U-shaped handle members 2 and 3 are employed and 50 secured to the bag at opposite sides of the

hinged frame 4, which forms the mouth of the bag.

The members 2 and 3 are identical and present a pair of opposed flat inner faces 5 and 6 which are brought together when the handle members are used to lift the bag. 55

I have illustrated loops 7 of leather or some similar material sewed to the outer faces of the bag at each side of the mouth thereof and buckles 8 connecting the loops 60 7 with the extremities 9 of the handle members 2 and 3. It is to be understood, however, that the particular method of securing the handle members to the bag is immaterial. My invention resides in the provision 65 of a pair of snap fastener members 10 and 11 in the opposed faces 5 and 6 of the handle members. I have illustrated the female element 10 of the fastener as secured to the handle member 2, and the male element 11 fixed to the handle member 3. 70

It will thus be readily seen that by snapping the fastening members together the handle members are prevented from falling away from each other when the bag is set 75 down.

Although I have illustrated a snap fastener for accomplishing this object, it is obvious that various other fastening devices might be employed with equal success to removably lock the handle members together. 80

To unlock the handle members when it is desired to open the bag, it is merely necessary to insert the thumb and forefinger between the members spreading or forcing 85 them apart as shown clearly in Fig. 2.

Various slight changes and alterations might be made in the general form of the parts described without departing from my invention, and hence I do not wish to limit 90 myself to the precise details set forth, but shall consider myself at liberty to make such slight changes and alterations as fairly fall within the spirit and scope of the appended claims. 95

I claim:

1. A hand bag handle comprising a pair of handle members adapted to be hingedly secured to a hand bag at opposite sides of the mouth thereof, and means for removably 100

locking said members together when the bag is in closed position, said means comprising coacting locking devices positioned on the opposed inner faces of the handle members and registering with each other.

2. A hand bag handle comprising a pair of handle members adapted to be hingedly secured to a hand bag at opposite sides of

the mouth thereof, and means for removably locking said members together when the bag is in closed position, said means comprising snap fastener members secured to the opposed inner faces of the handle members, and normally concealed by said members.

HORACE EVERETT WALTER.
